UNITED STATES PATENT OFFICE

146,514

DESIGN FOR A PLATE OR SIMILAR ARTICLE

Harry A. Malinowski, Meriden, Conn., assignor to The Ellmore Silver Co., Inc., Meriden, Conn., a corporation of Connecticut

Application January 15, 1946, Serial No. 125,568

Term of patent 14 years

(Cl. D44—15)

To all whom it may concern:

Be it known that I, Harry A. Malinowski, a citizen of the United States, in the city of Meriden, county of New Haven, and State of Connecticut, have invented a new, original, and ornamental Design for a Plate or Similar Article, of which the following is a specification, reference being had to the accompanying drawing, forming a part thereof, in which

The dominant features of my new design are shown in full lines in the drawing. The border ornamentation is confined throughout to those portions shown in outline of the drawing.

I claim:

The ornamental design for a plate or similar article, substantially as shown and described.

HARRY A. MALINOWSKI.
